UNITED STATES PATENT OFFICE.

JOSIAH LETCHWORTH, OF BUFFALO, NEW YORK.

DESIGN FOR A HAME-LOOP.

Specification forming part of Design No. 5,260, dated September 12, 1871.

To all whom it may concern:

Be it known that I, JOSIAH LETCHWORTH, of the city of Buffalo, in the county of Erie and State of New York, have invented or produced a new and original Design for Hame-Loop, of which the following is a specification:

The upper ends of the hames of harness are usually held together by a leathern strap which passes around the ends of the hames and through a staple or loop which is driven into the hame from the back side for the purpose of retaining the strap in place. Heretofore this loop has been made from round wire of suitable size bent into the required shape. My design consists of a hame-loop in which the outer or exposed portion is flattened so as to give to the loop the shape and contour shown in the accompanying drawing, in which—

Figure I is a side elevation of a portion of a hame provided with my new design for loop. Fig. II is a back view of the same.

Like letters of reference designate like parts.

A is the hame proper or wooden portion thereof. b is the strap of iron which is attached to

the back of the hame, and C my new design for loop.

From the drawing it will be perceived that the loop portion of the staple is flattened so as to increase its width laterally and give it a plane outer face, which, when viewed from the back or outer surface of the hame, is bounded by an elongated ellipse, while the prongs of the loop or staple are round. This shape and configuration can readily be given to the loop by the machine which bends the wire by subjecting that portion of the wire to pressure between suitable dies. The plane outer face of the loop may be ornamented by impressing upon it any suitable device, although I do not claim such ornamentation as a part of my design, which is limited to the shape and contour of the outer or face portion of the loop.

What I claim is—

The design for a hame-loop, as shown and described.

JOSIAH LETCHWORTH.
